This invention has reference to load tap changers for power transformers as applied, for instance, to maintain a constant secondary voltage with a variable primary voltage, to control the flow of reactive kva. between two generating systems, and to control the division of power between branches of loop circuits, etc.

It is a general object of this invention to provide improved load tap changers for polyphase transformers, in particular polyphase high voltage power transformers.

A further object of this invention is to provide load tap changers for polyphase high voltage power transformers which are considerably more compact, and involve considerably smaller manufacturing cost, than comparable prior art load tap changers.

Load tap changers include selector switches and transfer switches. The selector switches serve the purpose of selecting a particular tap on a tapped transformer winding intended to be connected into an electric circuit. Selector switches do not carry any load currents at the time a particular tap is selected, i.e. they are not required to interrupt or close on current-carrying circuits. This task is performed by the transfer switches. The latter perform all switching operations under load. Therefore all arcing is restricted to the transfer switches, the selector switches merely selecting the particular transformer tap to which the load is to be transferred.

Polyphase transformers require a selector switch and a co-operating transfer switch for each phase of the circuit. The selector switch and the transfer switch of each phase must be electrically insulated from the selector switch and the transfer switch of each other phase according to the full voltage between phases. For this reason it has become common practice to subdivide polyphase transformers into separate transformer units. Each such single phase unit comprises a separate tank, a separate single phase transformer, a separate load tap changer, and a separate drive for the latter. A plurality of such single phase units are integrated into a transformer bank. Transformer banks tend to be extremely bulky.

It is, therefore, another object of this invention to provide load tap changers which are less bulky than the load tap changers normally associated with transformer banks including a plurality of separate single phase transformer units.

It is frequently possible to reduce the aggregate size of a polyphase transformer including load tap changing means by arranging all the phases of such a transformer and the selector switches and the transfer switches of all the phases in a common tank. Where the voltage of a given polyphase transformer is high and its power large, the size of such transformers and of their associated load tap changing means tends to become intolerably large, and often exceeds the bulk limits required for transportation via rail, i.e. on railroad cars.

It is, therefore, another object of this invention to provide polyphase high voltage load tap changers which lend themselves to be combined with polyphase transformers whose various phase windings are arranged in a common

2

tank, i.e. built into the common tank, which load tap changers are extremely compact and add relatively little to the bulk of the composite transformer and load tap changer unit.

5 In the method of tap changing a current limiting device must be employed during each transition period from one tap position to the other. Such current limiting devices may either be center tapped reactors or resistors. This invention is particularly concerned with load tap changers wherein resistors are used as current limiting devices.

10 Load tap changers utilizing resistors as current-limiting devices and fast operating transfer switches are known, or referred to, as "Jansen" type load tap changers. This type of load tap changers has important advantages over

15 load tap changers of other kinds. In this type of load tap changers the current-limiting resistors are in parallel with respect to the load current and in series with respect to the circulating currents which flow during transition times between tap changes. This makes it possible to reduce

20 the resistance of the current limiting resistors to relatively low ohmic values without giving rise to large circulating currents. In "Jansen" type tap changers the movable contacts of the transfer switches move at high speeds, or with

25 a snap action, wiping over the fixed contacts to which the current limiting resistors are connected. As a result of this fast motion the transition periods during which the current limiting resistors must carry load currents are very short, say in the order of a few hundredths of a second. This has two significant advantages: The cur-

30 rent limiting resistors can be made very small and the voltage fluctuation resulting from tap changes insignificant. The rapid operation of the transfer switches is produced by stored energy means, preferably wound up springs which are maintained in a pre-wound, or pre-

35 loaded, condition in readiness for the next tap changing operation. Load tap changers of the "Jansen" type are well known in the art and have been described in many printed publications such as, for instance, the book by H. P. Young, Electric Power Control Systems, London, 40 England, Chapman & Hall Ltd., 1942, and reference may be had to such publications for a more complete description of "Jansen" type load tap changers, and the structural features and operating characteristics thereof.

45 It is another object of this invention to provide improved "Jansen" type load tap changers for polyphase high voltage power transformers.

The foregoing and other general and special objects of the invention and advantages thereof will appear more clearly from the ensuing particular description of the 50 invention as illustrated in the accompanying drawings, wherein:

FIGS. 1a and 1b are substantially a vertical section of a high voltage polyphase load tap changer embodying the present invention and comprising a plurality of selector switches, a plurality of transfer switches cooperating with the selector switches and drive means for both the selector switches and the transfer switches, FIG. 1a showing the left portion of the structure and FIG. 1b showing the right portion of the structure, both FIGS. 1a and 1b being complementary, FIG. 1a showing at the right side thereof some structural detail which is also shown in FIG. 1b to the left side thereof;

FIG. 2 is a top plan view of one of the selector switches and of one of the transfer switches of the structure of FIG. 1;

65 FIGS. 3a-3c are top-plan views of the three transfer switches of the structure of FIG. 1; and

FIG. 4 is a connection diagram of one phase of a polyphase transformer provided with a load tap changer embodying the present invention.

70 Referring now to the drawings, the structure shown in FIGS. 1 and 2 is intended to be accommodated within a

transformer tank having a cover on the top thereof. Neither the transformer tank nor the tank cover have been shown in FIG. 1. The cover of the tank of the transformer defines an opening which is covered by a part which may be referred to as a sub-cover. Reference numeral 10 has been applied in FIG. 1 to indicate the aforementioned sub-cover. Sub-cover 10 supports a vessel 11 of insulating material including a bottom 12. The lateral walls of vessel 11 are formed by an insulating cylinder or tube as widely applied in high voltage engineering. Vessel 11 is filled with an appropriate insulating liquid such as insulating oil. The bottom 12 of vessel 11 is provided with an opening 13 normally closed by a screw for draining oil from vessel 11. Tubular switch support 14 is arranged inside of vessel 11 in coaxial relation thereto. Support 14 is made of insulating material and houses three transfer switches 15, 16 and 17 which are arranged in coaxial relation to each other and to support 14 and vessel 11 and stacked one above the other. Transfer switches 15, 16, 17 are of the rotary type and are mounted on, and operated by, a common shaft 18 adapted to insulate each transfer switch from the others. As clearly shown in FIG. 2 each transfer switch comprises a set or group of movable contacts 19 adapted to cooperatively engage a set or group of circularly arranged fixed contacts 21. The set or group of contacts 19 is pivotally supported at 19a on a rotatable contact carrier 20. Contacts 19 are arranged along a sector of a circle whose center 19a is spaced from the axis of rotation of contact carrier 20. The fixed contacts 21 are supported on the inner surface of the aforementioned insulating cylinder or insulating tube 14. When contact carrier 20 and movable contacts 19 are operated, fixed contacts 21 are sequentially engaged by movable contacts 19, the latter performing a composite rotary and radial motion as set forth more in detail in U.S. Patent 2,680,790 to B. Jansen. The two movable contacts 19 on both ends of the sector of movable contacts 19 are main contacts, and the intermediate contacts of the sector of movable contacts 19 are switch-over contacts. In a like fashion the two contacts on both ends of the sector of fixed contacts (indicated in some of the figures by reference character 22) 21 are main contacts and the intermediate contacts of the sector of fixed contacts 21 are switch-over contacts (indicated in some of the figures by reference character 23). The aforementioned fixed main contacts 21 are conductively connected to the particular tap of the transformer winding which has been selected, while the aforementioned fixed switch-over contacts 21 are conductively connected to switch-over resistors or tap-changing resistors 24 in the fashion shown in FIG. 4.

Each transfer switch 15, 16, 17 comprises in essence three sector-shaped spaces of which one is occupied by the set of movable contacts 19 and the two others 25 are occupied by the aforementioned switch-over or tap-changing resistors 24. The location of the latter has been clearly shown in FIG. 2 as well as in FIGS. 3a-3c.

The carriers 20 for the movable contacts 19 are secured to composite shaft 18. This shaft comprises tubular sections 26 of insulating material alternating with sections formed by metal rods 27. Each of the two sections formed by metal rods 27 is interposed between a pair of sections 26 of tubular insulating material. The latter sections 26 separate and insulate each transfer switch 15, 16, 17 from the transfer switch or transfer switches immediately adjacent thereto.

Reference character 28 has been applied to indicate annular members for controlling the voltage distribution, i.e. the distribution of the electric field, around transfer switches 15, 16, 17 along parts 11 and 14. At least two such voltage control members 28 are arranged at each axial end of each transfer switch 15, 16, 17. As shown in FIG. 1 some of the voltage distribution control rings 28 are arranged inside of insulating tubing 14 and supported by the latter, and others are arranged outside of

vessel 11 and are supported by the latter. All of the voltage distribution control rings 28 are arranged in coaxial relation to parts 11, 14 and 18.

Since contacts 19 and 21 of transfer switches 15, 16, 17 part while carrying load currents arcs are kindled between these contacts incident to parting thereof, and these arcs form hot, ionized products of arcing. In order to avoid discharge of hot products of arcing formed in lower transfer switches to the arcing zones of the transfer switches arranged at a relatively higher stack level, transfer switches 15, 16, 17 are angularly displaced. In three phase transformers comprising three transfer switches 15, 16, 17—one for each phase—the angular displacement of the three transfer switches is 120 degrees. This has been shown in FIGS. 3a-3c of which each figure is a horizontal section at right angles to shaft 18 and of which each figure shows in top-plan view one of the three transfer switches 15, 16, 17.

Transfer switches 15, 16, 17 are operatively related to rotary selector switches 30, 31 and 32, i.e. transfer switch 15 is operatively related to selector switch 30, transfer switch 16 is operatively related to selector switch 31 and transfer switch 17 is operatively related to selector switch 32. Selector switches 30, 31 and 32 are stacked substantially in the same fashion as transfer switches 15, 16 and 17. Transfer switch 15 and selector switch 30 are arranged substantially at the same level, transfer switch 16 and selector switch 31 are arranged substantially at the same level, and transfer switch 17 and selector switch 32 are arranged substantially at the same level. The three selector switches 30, 31 and 32 are mounted on a common tubular insulating shaft 29. Switches 15 and 30 are arranged in the same phase of a three phase circuit, e.g. phase U. In a similar fashion switches 16 and 31 are arranged in the same phase of a three phase circuit, e.g. phase S. Finally switches 17 and 32 are arranged in the third phase or phase T of a three phase circuit. Switches 15 and 30 are interconnected by relatively short, substantially horizontal leads 33, switches 16 and 31 are interconnected by relatively short, substantially horizontal leads 34 and switches 17 and 32 are interconnected by relatively short and substantially horizontal leads 35.

Each selector switch 30, 31, 32 comprises a plurality of fixed radially outer contacts 36 of which each is secured to an insulating rib 37. Fixed contacts 36 are adapted to be cooperatively engaged by the two bridge elements or bridge contacts 38 which may be turned about the center of a circle along which fixed contacts 36 are positioned. The current-carrying bridge elements or bridge contacts 38 are mounted on insulating tube 29. Insulating tubes 39 extend parallel to insulating tube 29—i.e. both are vertical—and the latter support slip rings 40 clearly shown in FIG. 2 for connecting fixed leads to rotary bridge contacts 38. As shown in FIG. 1 annular members or rings 41 are arranged above each fixed contact 36 of each selector switch 30, 31, 32 for controlling the voltage distribution in the region of contacts 36. Annular metal members or rings 28' for the control of the voltage distribution in axial direction are also arranged on the top and at the bottom of the stack formed by the three selector switches 30, 31, 32.

Insulating tubes 39 integral with the stack of selector switches 30, 31, 32 are operable by means of a Geneva gear 42 shown in FIG. 1 arranged above the stack of selector switches 30, 31, 32. Geneva gears are widely applied in the art for operating selector switches of load tap changers and, therefore, Geneva gear 42 provided at the top of the stack of selector switches 30, 31, 32 does not call for a detailed description. Gear train 43 arranged above Geneva gear 42 is provided for operating the latter. Gear train 43 is operated from a shaft 45 by the intermediary of a transmission which may include a clutch or coupling 44. Shaft 45 is driven by an electric motor (not shown) which drives also the three trans-

fer switches 15, 16, 17 shown to the left of FIG. 1. This is achieved by means of gear 46 and an eccentric 47 operating a link or rod 48 loading a spring 49 upon rotation of shaft 45. Reference numeral 50 has been applied to indicate a tripping latch for releasing spring 49 when the particular taps intended to be inserted into the load circuit have been selected by means of the three selector switches 30, 31 and 32. Operation of the latch 50 results in an instantaneous movement of the current carrying contacts 38 of the three transfer switches 15, 16, 17 from their original positions to their pre-selected positions. Operation of the three transfer switches 15, 16, 17 by spring 49 is effected by the intermediary of an eccentric to which reference character 51 has been applied. The aforementioned drive comprising spring 49 and the transmission means for loading the same and for tripping the same are arranged within a gear housing 52 which is mounted on top of horizontal plate or cover 10 on the top of the transformer tank. Gear housing 52 is provided on the upper side thereof with an opening or window 53 making it possible to readily determine the particular position of the stack of transfer switches 15, 16, 17 and to inspect the constituent parts or elements of the drive housed within gear housing 52.

Referring now more particularly to FIG. 4, this figure shows to the left thereof three windings 100 of a polyphase transformer. All three windings 100 pertain to the same phase—say phase U—and only the center winding 100 is tapped. The center winding 100 has ten taps of which each is connected to one of the ten fixed contacts 36 of one of the selector switches, say selector switch 30. In order to make it clear that the center windings of the other phases S, T are also tapped and also connected to selector switches in the same fashion as the center winding of phase U, the reference characters 31 and 32 have been added in parentheses in FIG. 4 after reference character 30. The FIGURES 1 to 10 at the left of FIG. 4 have been applied to distinguish between the ten fixed contacts 36 of selector switch 30. Transfer switch 15 has been shown to the right of the selector switch 30 and reference characters 16 and 17 have been added in parentheses after reference character 15 to indicate that the transfer switches 16 and 17 are related in the same fashion to selector switches 31 and 32 as transfer switch 15 is related to selector switch 30. Each transfer switch 15, 16, 17 is provided with six fixed contacts 21 of which each of the four inner contacts 21 is connected to one of four tap changing resistors 24. The latter are, in turn, connected to the rotary contacts 38 of selector switches 30, 31, 32 by the intermediary of leads 33, 34, 35.

Reference numeral 54 has been applied to indicate a reversing switch of the kind widely applied in connection with load tap changers. Reversing switch 54 comprises a fixed center contact K and four additional fixed contacts A, A', B, B'. Lead 101 connects the lower terminal of the upper transformer winding 100 to the fixed contact A' of the reversing switch 54 and lead 102 connects the upper terminal of the lower transformer winding 100 to the fixed contact B' of the reversing switch 54. Fixed contacts A and B of reversing switch 54 are connected by leads 103 and 103a to the upper terminal of transformer center winding 100. Fixed center contact K of reversing switch 54 is connected by lead 104 to the support 20 of movable contacts 19 of the transfer switch 15. In the position of the reversing switch 54 shown in FIG. 4, the fixed contacts A and A' are conductively interconnected by movable contacts C and the fixed contacts K and B' are conductively interconnected by the movable contact D. The current path of phase U shown in FIG. 4 is as follows: upper transfer winding 100, lead 101, fixed contact A', movable contact C, fixed contact A, lead 103, center winding 100, fixed contact 36 of selector switch 30 at tap number seven, bridge contact 38, slip ring 40, lead 33, lead 105, upper fixed contact

5 of transfer switch 15, movable contact 19 of transfer switch 15 engaging the aforementioned fixed contact 21 thereof, contact support 20, lead 104, fixed contact K of reversing switch 54, movable contact D, fixed contact B', lead 102, lower transformer winding 100.

In the embodiment of the invention shown in FIGS. 1, 2 and 3a, 3b, 3c each transfer switch comprises but one single substantially sector-shaped set of movable contact fingers 19 and one single set of fixed circularly arranged contacts 21 cooperating with contact fingers 19. Where prevailing current intensities are very large it may be necessary, or desirable, to provide each transfer switch 15, 16, 17 with more than one substantially sector-shaped set of movable finger contacts 19, and with an equal number of sets of fixed circularly arranged contacts 21. The aforementioned sets of movable and fixed contacts are connected in parallel into each phase of a polyphase circuit, thus limiting the current carrying duty which must be assigned to each single set of contacts. In such a plural contact set arrangement there is less room within the space occupied by the transfer switches 15, 16, 17 for accommodating tap changing resistors 24.

According to FIG. 4 tap number seven is included in the circuit of the transformer and the load tap changer thereof. Assuming now that it is desired to change from tap number seven to tap number eight. Such a change involves the following steps to be carried out in the following sequence: Contact 38 which, heretofore, has been in engagement with the fixed selector switch contact number six is moved from the latter position into engagement with fixed selector switch contact number eight. This change of position of one of contacts 38 of each selector switch 30, 31, 32 does not involve the flow of any circulating currents. Nor does it involve any change in regard to the active windings of the transformer. Concomitant with the aforementioned change of the position of one of contacts 38 of each of the selector switches 30, 31, 32 the spring 49 for instantaneous or snap-action operation of transfer switches 15, 16, 17 is loaded, and thus readied to effect an instantaneous operation of said transfer switches. Upon tripping of latch 50 the movable set of contacts 19 of each selector switch 15, 16, 17 perform a composite or rolling motion thereby sequentially engaging the fixed contacts 21 thereof. As a result of this motion the following switching operations are performed sequentially. The upper tap changing resistor 24 of FIG. 4 is inserted into the circuit, the two upper tap-changing resistors 24 of FIG. 4 are inserted into the circuit, the two tap changing resistors arranged in the center of FIG. 4 shunt the part of center winding 100 situated between taps number seven and number eight for a very short period of time, the two lower tap-changing resistors 24 of FIG. 4 are inserted into the circuit, but the lowest tap-changing resistor of FIG. 4 is inserted into the circuit, and finally only the lowest of movable contact 19 engages the lowest fixed contact 21 providing a direct current path not including any of the tap-changing resistors 24. At this point of the tap changing operation contact 38 engaging fixed contact 36 of tap number seven does not carry any current any longer, all the current being carried by the other contact 38 in engagement with fixed contact 36 of tap number eight.

The next operation of the load tap changer may either 65 consist in a return of the constituent parts thereof to their original positions indicated in FIG. 4, which is a reversal of the operation which has been previously described in detail, or the next operation of the load tap changer may consist in a switching operation from taps number eight of selector switches 30, 31, 32 to taps number nine thereof. The last mentioned operation is a duplication of the switching operation which has been described above, i.e. a switching operation from taps number seven of selector switches 30, 31, 32 to taps number eight thereof.

Provision of reversal switch 54 makes it possible to reduce the number of taps of center winding 100 for a given or predetermined control duty since it makes it possible to use the voltage in the tapped center winding 100 selectively either for the purpose of boosting or for the purpose of bucking.

It will be apparent from the foregoing that a polyphase load tap changer embodying the present invention comprises a plurality of substantially identical transfer switches 15, 16, 17 each connected into one phase of a polyphase circuit and superimposed in substantially coaxial relation to form a transfer switch stack. The transfer switches comprised in said stack are angularly displaced a number of degrees equal to 360 divided by the number of the phases of the polyphase transformer. As a result of this angular displacement the hot products of arcing formed at load current switching operations of the transfer switches which are arranged at relatively low levels of the aforementioned stack are substantially kept away from the arcing zones of the transfer switches which are arranged at relatively high levels of the aforementioned stack. The particular embodiment of the invention described above is a load tap changer for a three phase transformer and its transfer switch stack comprises three transfer switches. The three transfer switches are angularly displaced $360/3 = 120$ degrees, as best shown in FIGS. 3a, 3b and 3c. The aforementioned angular displacement of the constituent transfer switches 15, 16, 17 of the transfer switch stack is generally sufficiently effective to provide for a rapid dielectric recovery of the ionized gaps formed between the parting contacts of transfer switches 15, 16, 17. If desired baffles may be provided between the various levels of a stack of transfer switches to keep the hot products of arcing of one transfer switch away from the arcing zone of the other transfer switches and to control the upward flow of products of arcing in a predetermined desired fashion.

The aforementioned angular displacement of transfer switches 15, 16, 17, i.e. of the sets of fixed contacts 21 and the sets of movable contacts 19 thereof makes it necessary to angularly displace the tap-changing resistors 24 in the same fashion. This has been clearly shown in FIGS. 3a-3c in which structure the tap-changing resistors 24 of transfer switches 15, 16, 17 are angularly displaced 120 degrees.

It appears further from the foregoing that each of the transfer switches 15, 16, 17 of polyphase load tap changers embodying the present invention includes a plurality of fixed circularly arranged contacts 21, a set of movable contacts 19 and current-limiting tap change resistors 24 within the cylindrical space defined by said circularly arranged fixed contacts 21.

The present invention contemplates the use of transfer switches of the general type disclosed and claimed in United States Patent 2,680,790 to B. Jansen, Load Changeover Switch for Tapped Transformers Using a Combination of Contact Movements, June 8, 1954 and United States Patent 2,833,873 to B. Jansen, Multi-Pole Tap Switch for Changing Transformer Taps Under Load, May 6, 1958, and reference may be had to the two aforementioned patents as to further details in regard to the transfer switches intended to be used for carrying the present invention into effect.

Load tap changers embodying the present invention further comprise insulating means for insulating the constituent transfer switches 15, 16, 17 of the transfer switch stack in accordance with the voltage prevailing between phases. The aforementioned insulating means include the body of oil inside of vessel 11 in which the transfer switches 15, 16, 17 are immersed, and the aforementioned insulating means further include the common shaft 18 for jointly operating the constituent transfer switches 15, 16, 17 of the transfer switch stack which shaft is at least in part of insulating material.

It appears also from the foregoing that load tap

5 changers embodying the present invention comprise a plurality of substantially identical selector switches 30, 31, 32 each connected into one phase of a polyphase circuit and superimposed in substantially coaxial relation to form a selector switch stack arranged in proximity of, or immediately adjacent to, the aforementioned transfer switch stack. The vertical spacing of the constituent transfer switches of the transfer switch stack and the vertical spacing of the constituent selector switches of the selector switch stack is substantially equal. Hence each transfer switch and each selector switch pertaining to the same phase are situated at substantially the same level, and each transfer switch is operatively related to one of the selector switches by leads 33, 34, 35 which are substantially horizontal or, in other words, do not extend beyond the two horizontal planes which form the upper and the lower boundary of a pair of associated and cooperatively related transfer switches and selector switches. These leads are, therefore, arranged in equi-potential spaces, i.e. spaces throughout which there is substantially the same potential. To be more specific, the required insulation of the leads 33, 34, 35 between cooperating transfer switches and selector switches is but that called for by the difference in voltage between consecutive or contiguous taps. This is a minimum of insulation requirement. The tap change resistors 24 for limiting the flow of circulating currents incident to changing from one tap to another are preferably arranged within the above equi-potential areas, forming integral parts of the transfer switches 15, 16, 17 to which they are operatively related. The gear means for operating the transfer switches 15, 16, 17 and for operating the selector switches 30, 31, 32 are arranged on top of the transfer switch stack and on top of the selector switch stack.

It will also be apparent from the foregoing that the leads 33, 34, 35 operatively relating the transfer switch and the selector switch pertaining to the same phase do not cross with like leads operatively relating transfer switches and selector switches of other phases.

It is a feature inherent in the above described structure that the constituent switches 15, 16, 17 of the transfer switch stack and the constituent switches 30, 31, 32 of the selector switch stack may jointly be insulated against ground, which results in much more economical and compact structures than where cooperating pairs of transfer switches and selector switches are separately insulated against ground. Since the impulse strength of insulation against ground must be relatively high, this feature is one which is of considerable importance.

The common drive means for all transfer switches 15, 16, 17 and for all selector switches 30, 31, 32 of the load tap changer is a feature greatly reducing prime cost and space requirements. Since the volume of oil involved for insulating load tap changers embodying this invention is relatively small, and since inspection of the aforementioned common drive and of the switches integrated into the transfer switch stack and of the switches integrated into the selector switch stack is relatively simple, the cost of maintenance of load tap changers embodying the present invention are minimized.

Load tap changers embodying this invention lend themselves to manual as well as to automatic supervisory control.

It will be understood that although but one embodiment of the invention has been illustrated and described in detail, the invention is not limited thereto. It will also be understood that the structure illustrated may be modified without departing from the spirit and scope of the invention as set forth in the accompanying claims.

It is claimed:

1. A load tap changer for polyphase transformers comprising in combination with a plurality of tapped phase windings of a polyphase transformer:

(a) a horizontal cover plate;

- (b) an oil filled cylindrical vessel attached to said plate and projecting from the lower surface thereof;
  - (c) a plurality of stacked transfer switches each arranged within said vessel in coaxial relation thereto, each of said plurality of transfer switches including fixed contacts and movable contacts cooperating with said fixed contacts in a predetermined sequence;
  - (d) a shaft coextensive with the axis of said vessel projecting transversely through said cover plate for joint operation of said plurality of transfer switches;
  - (e) a plurality of groups of resistors arranged within said vessel each at substantially the same level as one of said plurality of transfer switches, the constituent resistors of each of said plurality of groups of resistors having a first end conductively connected to some of said fixed contacts of one of said plurality of transfer switches and the constituent resistors of each of said plurality of groups of resistors having a second end;
  - (f) a plurality of stack selector switches each arranged at substantially the same level as one of said plurality of transfer switches and one of said plurality of groups of resistors, each of said plurality of selector switches including a pair of rotary contacts, and each of said plurality of selector switches including a plurality of circularly arranged fixed contacts engageable by said pair of rotary contacts, each of said plurality of fixed contacts of each of said plurality of selector switches being conductively connected to one tap of one of said plurality of phase windings, and said pair of rotary contacts of each of said pair of selector switches being conductively connected to said second end of said constituent resistors of one of said plurality of groups of resistors;
  - (g) an insulating column parallel to said shaft providing fulcra for said pair of rotary contacts of each of said plurality of selector switches; and
  - (h) drive means for said plurality of transfer switches and for said plurality of selector switches supported by said cover plate, said drive means including a loaded operating spring arranged above said cover plate for operating said first shaft and a Geneva gear drive for gang operating said pair of rotary contacts of each of said plurality of selector switches.
2. A load tap changer for polyphase transformers comprising in combination with a plurality of tapped phase windings of a polyphase transformer:
- (a) an oil filled substantially cylindrical vessel;
  - (b) an insulating cylinder arranged inside said vessel in coaxial relation thereto;
  - (c) a plurality of stacked transfer switches each arranged within said vessel in coaxial relation thereto, each of said plurality of transfer switches including fixed contacts and movable contacts cooperating with said fixed contacts in a predetermined sequence, said fixed contacts of each of said plurality of transfer switches being supported by said insulating cylinder;
  - (d) a plurality of groups of current-limiting resistors arranged within the space bounded by said insulating cylinder each arranged at substantially the same level as, one of said plurality of transfer switches, the constituent resistors of each of said plurality of groups of resistors having a first end conductively connected to some of said fixed contacts of one of said plurality of transfer switches and the constituent resistors of each of said plurality of groups of resistors having a second end; and
  - (e) a plurality of stacked rotary selector switches each arranged at substantially the same level as one of said plurality of transfer switches and one of said plurality of groups of current-limiting resistors, each of said plurality of selector switches including a pair of rotary contacts, and each of said plurality of selector switches including a plurality of circularly ar-

- ranged fixed contacts engageable by said pair of rotary contacts, each of said plurality of fixed contacts of each of said plurality of selector switches being conductively connected to one tap of one of said plurality of phase windings, and said pair of rotary contacts of each of said pair of selector switches being conductively connected to said second end of said constituent resistors of one of said plurality of groups of resistors.
3. A load tap changer for polyphase transformers comprising in combination with a plurality of tapped phase windings of a polyphase transformer:
- (a) a plurality of stacked transfer switches each including fixed contacts and movable contacts cooperating with said fixed contacts in a predetermined sequence;
  - (b) a vertical shaft for gang-operating said plurality of transfer switches including insulating means for insulating said plurality of transfer switches from each other;
  - (c) a plurality of stacked groups of resistors each arranged at substantially the same level as one of said plurality of transfer switches, the constituent resistors of each of said plurality of groups of resistors having a first end conductively connected to some of said fixed contacts of one of said plurality of transfer switches and the constituent resistors of each of said plurality of groups of resistors having a second end;
  - (d) a plurality of stacked selector switches each arranged at substantially the same level as one of said plurality of transfer switches and one of said plurality of groups of resistors, each of said plurality of selector switches including a pair of rotary contacts, and each of said plurality of selector switches including a plurality of circularly arranged fixed contacts engageable by said pair of rotary contacts, each of said plurality of fixed contacts of each of said plurality of selector switches being conductively connected to one tap of one of said plurality of phase windings, and said pair of rotary contacts of each of said pair of selector switches being conductively connected to said second end of said constituent resistors of one of said plurality of groups of resistors;
  - (e) a vertical insulating column in the center of said plurality of selector switches providing fulcra for said pair of rotary contacts of each of said plurality of selector switches;
  - (f) additional vertical insulating columns providing mechanical ties between each of said pair of rotary contacts of each of said plurality of selector switches; and
  - (g) a Geneva gear drive arranged above said plurality of selector switches cooperatively engaging the upper ends of said additional insulating columns for gang operating said plurality of selector switches.
4. A load tap changer for polyphase transformers comprising in combination with a plurality of tapped phase windings of a polyphase transformer:
- (a) a plurality of stacked, jointly operable rotary selector switches electrically insulated from each other, each being at a predetermined potential, each of said plurality of selector switches including a plurality of circularly arranged fixed contacts each connected to one of the taps of one of said plurality of tapped phase windings of said transformer, and each of said plurality of selector switches further including a pair of movable contacts each cooperating with said plurality of fixed contacts;
  - (b) a plurality of stacked jointly operable transfer switches electrically insulated from each other, each being at a predetermined potential, each of said plurality of transfer switches having a plurality of circularly arranged fixed contacts including outer main contacts and inner auxiliary contacts and each of

said plurality of transfer switches further having a plurality of movable contacts each cooperating in a predetermined sequence with one of said plurality of fixed contacts, each of said plurality of transfer switches being arranged at substantially the same level as one of said plurality of selector switches being at the same potential; and

(c) a plurality of groups of switching resistors, the constituent resistors of each of said plurality of groups of switching resistors having a first end and having a second end and being connected with said first end thereof to said pair of movable contacts of one of said plurality of selector switches, and being connected with said second end thereof to said fixed auxiliary contacts of one of said plurality of transfer switches, and each of said plurality of groups of switching resistors being arranged at substantially the same level as one of said plurality of selector switches and one of said plurality of transfer switches.

5. A load tap changer for polyphase transformers comprising in combination with a plurality of tapped phase windings of a polyphase transformer:

(a) a plurality of stacked jointly operable rotary selector switches electrically insulated from each other and at different potentials, each of said plurality of selector switches having a plurality of circularly arranged fixed contacts each connected to one of the taps of one of said plurality of phase windings of said transformer and each of said plurality of selector switches having a pair of movable contacts each cooperating with said plurality of fixed contacts;

(b) means for controlling the voltage distribution along the stack formed by said plurality of selector switches tending to establish a plurality of equipotential zones each occupied by one of said plurality of selector switches;

(c) a plurality of stacked jointly operable transfer switches electrically insulated from each other each being at a different potential, each of said plurality of transfer switches having a plurality of circularly arranged fixed contacts including outer main contacts and inner auxiliary contacts and each of said plurality of transfer switches further having a plurality of movable contacts cooperating in a predetermined sequence with one of said plurality of fixed contacts, each of said plurality of transfer switches being arranged at substantially the same level as one of said plurality of selector switches;

(d) means for controlling the voltage distribution along the stack formed by said plurality of transfer switches tending to establish a plurality of equipotential zones each occupied by one of said plurality of transfer switches;

(e) a plurality of groups of switching resistors, each of said plurality of groups of switching resistors being arranged at substantially the same level as one of said plurality of transfer switches, the constituent resistors of each of said plurality of groups of switching resistors having a first end and having a second end and being connected with said first end thereof to said fixed auxiliary contacts of one of said plurality of transfer switches; and

(f) a plurality of substantially horizontally extending pairs of leads, each of said plurality of pairs of leads conductively connecting said pair of movable contacts of one of said plurality of selector switches to said second end of the constituent resistors of one of said plurality of groups of switching resistors, and each of said plurality of pairs of leads being arranged in one of said plurality of equipotential zones occupied by one of said plurality of selector switches and in one of said plurality of equipotential zones occupied by one of said plurality of transfer switches.

6. A load tap changer for three phase transformers

75

comprising in combination with a plurality of tapped phase windings of a three phase transformer:

(a) a plurality of stacked jointly operable rotary selector switches electrically insulated from each other and at different potentials, each of said plurality of selector switches having circularly arranged fixed contacts conductively connected to the taps of one of said plurality of phase windings of said transformer and a pair of movable contacts cooperating with said fixed contacts;

(b) a plurality of groups of stacked switching resistors having a spacing substantially equal to the spacing of said plurality of selector switches, the constituent resistors of each of said plurality of groups of switching resistors having a first end and having a second end and being conductively connected with said first end thereof to said pair of movable contacts of one of said plurality of selector switches; and

(c) a plurality of stacked jointly operable rotary transfer switches electrically insulated from each other and at different potentials, each of said plurality of transfer switches having a plurality of circularly arranged fixed contacts including outer main contacts and inner auxiliary contacts and each having an equal number of movable contacts cooperating in a predetermined sequence with said fixed contacts, said plurality of transfer switches having a spacing substantially equal to the spacing of said plurality of selector switches and said fixed auxiliary contacts of each of said plurality of transfer switches being conductively connected to said second end of said constituent resistors of one of said plurality of groups of switching resistors, said plurality of fixed contacts and said movable contacts of each of said plurality of transfer switches being angularly displaced 120 degrees and encompassing an angle of less than 180 degrees, each of said plurality of groups of switching resistors being arranged immediately adjacent said plurality of fixed contacts and immediately adjacent to said movable contacts of one of said plurality of transfer switches and angularly displaced 120 degrees.

7. A load tap changer as specified in claim 6 comprising a common vertical shaft for jointly operating said plurality of transfer switches, said shaft comprising insulating sections alternating with metallic sections, each of said insulating sections being arranged between contiguous of said plurality of transfer switches and each of said metallic sections being substantially coextensive with the height of one of said plurality of transfer switches.

8. A load tap changer for polyphase transformers comprising in combination with a plurality of tapped phase windings of a polyphase transformer:

(a) a plurality of stacked jointly operable rotary selector switches electrically insulated from each other and at different potentials, each of said plurality of selector switches having circularly arranged fixed contacts conductively connected to the taps of one of said plurality of phase windings of said transformer and a pair of movable contacts cooperating with said fixed contacts;

(b) a plurality of groups of current-limiting impedances, each of said plurality of groups of impedances being arranged at substantially the same level as one of said plurality of selector switches, the constituent impedances of each of said plurality of groups of impedances having a first end and having a second end and being conductively connected with said first end thereof to said pair of movable contacts of one of said plurality of selector switches;

(c) cylindrical contact supporting means of insulating material; and

(d) a plurality of stacked jointly operable rotary transfer switches electrically insulated from each other and at different potentials, each of said plurality of

transfer switches having a plurality of circularly arranged fixed contacts including outer main contacts and inner auxiliary contacts supported by said cylindrical contact supporting means and each having movable contacts cooperating in a predetermined sequence with said fixed contacts, each of said plurality of transfer switches being arranged at substantially the same level as one of said plurality of selector switches and one of said plurality of groups of impedances, said fixed auxiliary contacts of each of said plurality of transfer switches being conductively connected to said second end of said constituent impedances of one of said plurality of groups of impedances, said plurality of transfer switches being angularly displaced a number of degrees substantially equal to 360 divided by the number of phases of said polyphase transformer.
